UNITED STATES PATENT OFFICE.

WILLARD S. McKUSICK, OF DENMARK, MAINE.

SLED-KNEE.

No. 833,691.

Specification of Letters Patent.

Patented Oct. 16, 1906.

Application filed February 24, 1906. Serial No. 302,813.

To all whom it may concern:

Be it known that I, WILLARD S. McKUSICK, a citizen of the United States of America, and a resident of Denmark, county of Oxford, State of Maine, have invented certain new and useful Improvements in Sled-Knees, of which the following is a full and clear specification, reference being had to the accompanying drawings, in which—

10 Figure 1 is a detail perspective view of my improved device, and Fig. 2 is a perspective view showing its application to a sled.

The object of this invention is to provide an exceedingly strong, simple, and durable 15 device for connecting the runner to the cross-bar in such a manner that heavy loads may be borne by the cross-bars of the sled without undue strains upon the parts, as more fully hereinafter set forth.

20 The special improvement lies in constructing the knee of a single plate of sheet iron or steel bent upon itself to form a closed substantially triangular loop. The top plate of the loop fits against and supports the cross-bar and is provided with holes for the passage of the securing bolts or screws. The lower end of the loop is flattened, so as to bear squarely upon the upper edge of the runner.

25 To the accomplishment of this object and such others as may hereinafter appear the invention consists of the parts and combination of parts hereinafter fully described, and particularly pointed out in the appended 30 claim, reference being had to the accompanying drawings, forming a part of this specification, in which the same reference characters 35 designate like parts throughout both views.

The top plate *a* extends laterally beyond the loop *b* in order to give a broad support to 40 the cross-bar *c*. This lateral projection of the top plate extends inward. The plate from which the knee is formed is substantially the same width throughout, and its opposite edges are provided with notches *d*, 45 which when the plate is bent into shape are coincident with each other in a vertical plane. In these notches lie the vertical bolts or pins *e*, which secure the cross-bar and the knee *f* to the runner, these bolts or pins engaging 50 not only the notches in the edges of the knee, but also in notches in the side edges of the cross-bar. One end of the plate is welded to the under side of the top, as shown at *g*, and inclines upwardly and inwardly to form a 55 stiff brace.

What I claim, and desire to secure by Letters Patent, is—

In combination with a sled-runner and a cross-bar, a knee structure consisting of a 60 plate bent into a substantially triangular shape and having a top plate extended laterally and adapted to support the cross-bar and a bottom plate adapted to rest on the runner and an upwardly and inwardly inclined brace, the opposite edges of the top plate and the bottom plate being coincidentally notched, and pins or bolts fastened in the runner and engaging said notches.

In testimony whereof I hereunto affix my 70 signature, in the presence of two witnesses, this 3d day of January, 1906.

WILLARD S. McKUSICK.
